(57) **CLAIM**

The ornamental design for a radio communication device, as
shown and described.

DESCRIPTION

FIG. 1 is a front view of a radio communication device in
accordance with the present design;

FIG. 2 is a back view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The portions of the radio communication device shown in
broken lines form no part of the claimed design.
